ELECTRON MULTIPLIER

Richard L. Snyder, Jr., Glassboro, N. J., assignor
to Radio Corporation of America, a corporation
of Delaware

Application September 30, 1939, Serial No. 297,219

5 Claims. (Cl. 250—175)

My present invention relates to electron discharge tubes and particularly to improvements in electron multipliers.

The efficiency of an electron multiplier is determined to a large extent, upon its ability to focus or otherwise direct the electrons from one stage upon or to the next succeeding electrode. One factor inhibiting perfect focusing is the tendency of the electron stream to spread laterally when it has been augmented by more than a few stages of electron multiplication. This may result in the electrons spilling over the sides of the electrodes and creating tube noises.

Another difficulty encountered in the operation of multi-stage electron multipliers is that when the electron stream has been increased by several stages of electron multiplication, positive ions may be generated in the residual gas. This phenomenon has been observed to exist even in the most thoroughly evacuated tubes. These positively charged particles flow in a direction opposite to the general direction of the electron stream and may impinge upon the primary-electron emitting cathode, or upon an intermediate secondary-electron emitter, where they release still more electrons. The electron current may thus be augmented to such a degree as to render it uncontrollable. This building up of the electron current is limited only by the so-called "space charge effect" and may result in an equilibrium of the output current, i. e., the output current may no longer accurately reflect variations in the input current.

Rajchman and Pike, in their copending application Serial No. 171,916, filed October 30, 1937, describe an open sided electrode assembly for electron multipliers wherein each emitter electrode has a surface which extends into the space between the cathode and anode whereby these several surfaces constitute a barrier to the passage of ions in the anode-cathode directions. Such construction bars or entraps and dissipates the vast majority of ions adjacent their area of origin and thereby ensures improved performance. The improved performance is best evidenced by the fact that the output current is directly proportional to the input current substantially irrespective of the intensity of the electron stream impinging upon the output electrode. It has been observed, however, that when the Rajchman and Pike tubes are operated at or close to their maximum output, there is a tendency for the tube to become "noisy."

I have discovered that this undesired result may be attributed to the escape of some ions from

the "ion traps" due to the distorted contour of the equipotential lines which may be present adjacent the lateral edges of the open sided electrode assembly due to the proximity of the glass walls of the envelope.

As a result of numerous observations, I conclude that these escaped ions flow to the low current (input) end of the device, where they apparently impinge upon the inner surface of the container, thus creating a positive charge thereon. When the positive charge on the tube wall extends to the area which surrounds the cathode, the positive surface will draw some of the emitted primary or photo-electrons thereto. These negatively charged particles neutralize the positive charge on the glass wall and in so doing create an electrical disturbance within the tube. Such disturbance will ordinarily be of a continuing nature because the positive charge having been neutralized, the escaping ions will again be drawn thereto, followed later by the electrons from the cathode which provide the disturbance incident to the described neutralizing action.

Accordingly, the principal object of my present invention is to provide an electron multiplier wherein tube noises due to the flow of ions or to lack of perfect focusing of the electrons is substantially obviated.

As described in my copending application Serial No. 177,286 filed November 30, 1937, I have heretofore achieved the abovementioned general object in an electron multiplier of the type described in the said Rajchman and Pike application by supporting the electrode assembly on a plurality of spaced discs which extend to the tube wall and act as physical barriers to the passage of escaped ions. These discs are preferably each provided with a pair of baffles which span the open sides of the electrode assembly and serve to extend the equipotential surfaces between adjacent electrodes out and beyond the edges of said electrodes whereby the electrically charged particles generated within the assembly are constrained to remain within the desired boundaries instead of being drawn outwardly by the distorted field usually present adjacent the side edges of the multiplying electrodes.

I have now discovered that the same desirable results can be achieved in a more economical and facile manner (and without the use of auxiliary discs and baffles) by so shaping the electrodes that the electrons are focused inwardly toward the center of the next electrode. This permits the use of an extremely compact enclosed electrode assembly from which the ions cannot escape.

and one which, by reason of its simplicity of construction and ease of assembly, lends itself readily to mass production methods.

Other objects and advantages, together with certain details of construction, will be apparent and my invention itself will be best understood by reference to the following specification and to the accompanying drawing, wherein

Figure 1 is a sectional view on an enlarged scale taken on the line 1—1 of Fig. 3 and showing an electron multiplier embodying my invention:

Figure 2 is a view in perspective of one of the multiplying electrodes of the device of Fig. 1; and

Figure 3 is a side elevational view, partly in section, of the electron multiplier of Fig. 1.

The general arrangement of the electrodes may be similar to that claimed in copending application Serial No. 187,634 to Zworykin and Snyder, filed January 29, 1938. In the drawing, wherefore in like reference characters designate the same parts in all figures, T designates generally a highly evacuated cylindrical envelope or tube, the longitudinal axis of which is marked X. The tube has a pair of opposed, preferably flat, inner surfaces A and B, respectively, (see Fig. 3) and is provided with an inner radial partition C which extends from a point adjacent the central axis X to the inner wall thereof and serves to prevent the passage of electrons from the low voltage to the high voltage side of the tube. Considered from another aspect, the partition C serves to prevent the passage of any ions, which may escape the later described ion barriers, from being drawn to the low voltage side of the device. Perhaps more important is the fact that this partition C prevents cold discharge of electrons which might otherwise be caused by the high electric field which would otherwise exist between the high and low voltage sides of the device.

Where, as in the drawing, the device is provided with a photosensitive cathode P, the envelope is preferably constituted, in whole or in part, of glass, "Pyrex," or other suitable transparent material to permit light (exemplified by the line a) from an external source, not shown, to be shined upon the cathode. A grid G, which is preferably connected to the photo-sensitive cathode P and is supported between it and the inner wall of the glass envelope T, serves to prevent the accumulation of a positive charge upon the inner surface of the envelope. In addition to the grid G and cathode P, the tube contains a plurality of "intermediate" electron multiplying electrodes, designated 1 to 8, inclusive, which are mounted in staggered relation on opposite sides of a curved substantially arcuate median line m, which may be said to bisect the electron path which extends from the cathode P to and beyond the last mentioned multiplying electrode 8. Another electrode 9, which may extend to or across the median line m, comprises the last multiplying stage of the device. As described in copending application Serial No. 287,020, filed July 28, 1939, to Rajchman and Snyder, this final multiplying electrode 9 preferably comprises a C-shaped or "inflated U-shaped" plate having the open space between its inwardly directed terminal edges directed toward the source 8. The collector electrode or anode 10 is mounted within the oval defined by the inner surface of the last multiplying electrode 9. The collector anode 10 may be of grid-like or other openwork construction to permit the electrons from the source 8 to pass there-

through and to impinge the secondarily emissive surface of electrode 9 without substantial numerical diminution.

As indicated by the arrows on the dotted lines extending between the several electrodes, the electrons leaving the photosensitive cathode advance in the anode direction in travelling to the next higher numbered electrode by reason of the electrostatic fields which are generated therebetween when each is maintained at a fixed potential which is higher than that of its preceding (in point of electron travel) electrode.

It will be observed from an inspection of Fig. 1 that the emissive surface e of each of the multiplying electrodes 1 to 8 inclusive is non-cylindrical, or cup-shaped, or concave spherical construction, i. e. it is curved not only in the direction of the median line m (as in the prior art) but is also curved, in accordance with my present invention, in the transverse direction. The two directions of curvature are indicated by the crossed lines on the back of the emissive surface of the multiplying electrode shown in Fig. 2. This double curvature of the multiplying surfaces e provides an electrostatic field which directs the electrons inwardly toward the center of the next succeeding electrode.

It will also be observed from an inspection of Fig. 1 that the space between each multiplying electrode of both the inner (even numbered) and the outer (odd numbered) sets of electrodes is closed by an insulating rod R which serves as a support for two adjacent electrodes. A transverse linear non-emissive portion of each multiplying electrode adjacent each leading f (nearer the anode) and trailing g (nearer the cathode) edge is bent to fit snugly about the rods R without contacting the next electrode of the same set. Referring to Fig. 3, it will be seen that each multiplying electrode spans the entire distance between the opposed flat inner surfaces A and B of the tube or envelope T. Since these surfaces A and B close the sides of the electrodes and the rods R close the space between adjacent electrodes of the same set, the electrode assembly considered in its entirety may be said to comprise a "conduit" through which the electrons may travel from one electrode to another.

As shown more clearly in Fig. 2, the ends of the electrodes which lie adjacent the flat tube surfaces are preferably provided each with a rearwardly bent flange h which lends rigidity to the assembly. In order to reduce "dark current" (i. e. current which flows when the cathode is not illuminated but the electrodes are energized), it is preferable to round all of the edges of the electrodes along the areas where "field emission" might arise.

Another and important feature of my present invention resides in providing the trailing end of the multiplying electrodes with a preferably rounded extension j which projects beyond the leading edge of the next preceding multiplying electrode of the same (inner or outer) set. When the electrodes are energized these extensions j may be said to introduce an accelerating component into the electrostatic field between each opposite pair of electrodes without detrimentally affecting the focusing of the electron stream and without either increasing the number of electrodes or complicating the electrode assembly.

In manufacturing the electron multiplier in the form shown in Fig. 3, the glass envelope is made in two sections t1 and t2. The stem part

*t*₁ of the tube contains the flat inner base to which the insulating supporting rods *R* are affixed. The rods *R* may be of glass and made integral with the base *A*. The electrodes may thus 5 be mounted in place simply by sliding their complementary parts *f* and *g* about the rods *R*. The upper or cap portion *t*₂ is then fitted over the stem portion *t*₁ and sealed thereto, as indicated at *s*, and the tube pumped in usual manner 10 through a tip, not shown, on its lower rim. Since it will be understood that the leads for the several electrodes may extend through the base *A*, it would needlessly complicate the drawing to show them.

15 While my invention has been described as applied to an electron multiplier wherein the electrodes are mounted on opposite sides of an arcuate median line which extends between the cathode and anode, it will be apparent that my 20 invention is none the less applicable to tubes wherein the electrodes are arranged along a straight axis. It is to be understood, therefore, that the foregoing is to be interpreted as illustrative and not in a limiting sense, except as required by the spirit of the appended claims.

25 The term "non-cylindrical surface" as herein used is to be interpreted in its accepted geometrical sense. It is thus not intended to include a surface which lies in a single plane.

30 What is claimed is:

1. An electron multiplier comprising an evacuated envelope having a pair of opposed substantially flat inner walls, a cathode, an anode and a pair of sets of spaced multiplying electrodes extending between said flat walls and mounted in staggered relation on opposite sides of a median line which extends between said cathode and anode, and a plurality of insulating members supporting the multiplying electrodes of

each set, said insulating members extending between said flat walls and closing the spaces between the spaced electrodes of the same set.

2. An electron multiplier comprising an evacuated envelope having a pair of opposed substantially flat inner surfaces, a pair of rows of insulating supporting rods extending between said surfaces, and a pair of sets of spaced multiplying electrodes mounted on said supporting rods and spanning the space between said flat surfaces, 5 said supporting rods closing the spaces between the electrodes which they support.

3. An electron multiplier comprising an evacuated envelope having a pair of opposed inner surfaces, a pair of rows of insulating supporting 15 rods extending between said surfaces, a pair of sets of spaced multiplying electrodes mounted on said supporting rods, the electrodes of each set being spaced from each other to form a conduit through which electrons may travel from one 20 electrode to another, the side walls of said conduit comprising the said opposed surfaces of said envelope and the spaces between the electrodes of each set being closed by said supporting rods.

4. The invention as set forth in claim 3 where- 25 in one end of said conduit is closed by a multiplying electrode which spans the space between said sets of multiplying electrodes.

5. An electron multiplier comprising a cathode, an anode, and a set of multiplying surfaces 30 mounted in staggered relation on each side of a median line which extends between said cathode and anode, the trailing transverse edges of the multiplying electrodes of each set being bent inwardly toward said median line and projecting 35 beyond the leading edge of the next preceding electrode in the same set.
